UNITED STATES PATENT OFFICE.

WALTER LUFT, OF ELBERFELD, GERMANY.

CLOSURE FOR LADIES' WAISTS AND BLOUSES.

1,029,204.

Specification of Letters Patent. Patented June 11, 1912.

Application filed August 15, 1911. Serial No. 644,177.

To all whom it may concern:

Be it known that I, WALTER LUFT, residing at Mirkstrasse 35, Elberfeld, Rhenish Prussia, Germany, have invented new 5 and useful Improvements in Closures for Ladies' Waists and Blouses, of which the following is a specification.

My invention has for its object a new and original closure for ladies' garments and 10 particularly for blouses and waists the novelty of which consists in the manner of attaching press button members to strips or bands of textile fabric which is carried out in a simple and yet effective way.

15 I have illustrated my invention on the accompanying drawing on which—

Figure 1 is a top view of one strip of the new closure, Fig. 2 is a similar view of the other strip, Fig. 3 is a cross section along 20 line I—I of Fig. 1, Fig. 4 is a cross section along line II—II of Fig. 1, Figs. 5 and 6 are similar sections along lines III—III and IV—IV of Fig. 2.

Like letters of reference indicate like 25 parts in the drawings.

Referring to the said drawings it will be understood that my improved closure consists of the two strips or bands *a* and *b* made of any suitable material both strips 30 being as narrow and as light as possible in order to enable the closure to be attached or fastened to blouses of very thin stuff. To both of said strips are connected the members *c* and *d* of press buttons for which purpose the strips are woven partly in firm portions as at *e* and partly in pockets as at *f* the said pockets being closed at one longi-

tudinal edge of the ribbons and open at the opposite. Each pocket is provided with a hole *g* being woven or cut therein and having preferably firm edges in order to receive the members *c* and *d* of the press buttons one of which the stud member being inserted into the pocket and stuck through the hole *g* so that the head projects over the strip and 45 the button member is firmly held in position as shown. The cap member *d* which contains the spring may be made of any suitable construction it being provided around its opening *h* with a collar *m* and also introduced into the pocket of the strip or band *b* the collar *m* being stuck through the hole and thus the said member is also fitted in a 50 close contact with the band.

My new closure is of great importance to 55 garments and allows a quick opening of the same and may be manufactured at very low costs. It may be mentioned that instead of fitting the cap member with a spring the head of the stud member may be constructed 60 with spring action.

What I claim and desire to secure by Letters Patent is:

A garment closure comprising strips or bands, a plurality of pockets in each of said bands, one longitudinal edge of each of said pockets being open, and each of said pockets having an aperture for the reception of a press button.

WALTER LUFT. [L.S.]
